DESIGN FOR A FISHING SINKER

William D. Minser, Everett, Wash., assignor of one-half to Earl B. Schwenk, Seattle, Wash.

Application April 1, 1939, Serial No. 83,975

Term of patent 3½ years

To all whom it may concern:

Be it known that I, William D. Minser, a citizen of the United States, residing at Everett, in the county of Snohomish and State of Washington, have invented a new, original, and ornamental Design for a Fishing Sinker, of which the following is a specification, reference being had to the accompanying drawing, forming a part thereof.

In said drawing:

Figure 1 is a view in side elevation of a fishing sinker, showing my new design.

Fig. 2 is a top plan view thereof.

Fig. 3 is a front elevation; and

Fig. 4 is a rear elevation of said design.

I claim:

The ornamental design for a fishing sinker, as shown.

WILLIAM D. MINSER.
